UNITED STATES PATENT OFFICE

JESSUP SALISBURY, OF HAMDEN, CONNECTICUT, ASSIGNOR TO THE AMERICAN BUCKLE COMPANY, OF WEST HAVEN, CONNECTICUT, A CORPORATION OF CONNECTICUT

LOOP BUCKLE

Application filed June 28, 1929. Serial No. 374,391.

This invention relates to loop buckles having fixed inturned prongs for a strap engagement, and a relative sliding bar carrying means for protecting the points of the prongs. 5 The objects of the invention are to provide an effective strap holding buckle of simple construction; and to provide a reversible buckle having prongs and having means, operable by a taut strap threaded into the 10 buckle, for protecting the prong points.

The character of the invention may be best understood by reference to one illustrative device embodying the invention and illustrated by the accompanying drawing in 15 which the Figure 1 is an elevation of a loop buckle with prong points exposed; the Figure 2 is a similar elevation, but with prong points protected; the Figure 3 is a section taken on the dotted line 3—3 of the Figure 2 20 with a strap threaded therein; and the Figure 4 is a perspective view of a movable part.

The device, as illustrated, is a loop buckle preferably made of wire of which the middle portion is bent to form a button loop, and 25 the remaining end portions being bent in substantially rectangular form above the button loop and providing the buckle frame having the bar portions 1, the substantially parallel frame ends 2 and 3, and the aligned 30 arms 4 and 5, substantially parallel with the bar portions 1, the aligned arms 4 and 5 being provided with the inwardly turned and relatively spaced prongs 6 and 7, respectively, lying within the plane of the buckle frame 35 and directed toward the button loop. A bar 8 with attaching ends 9 and 10 looped around the frame ends 2 and 3, respectively, is mounted upon the frame for a relative sliding movement. The bar 8 is provided with means for 40 covering, and thus protecting, the points of the prongs 6 and 7 when the bar is moved into contact therewith. This bar 8 provided with such prong protecting means furnishes the novelty of this invention and may be constructed in any desired form; for the invention is not limited to any specific form of construction and the details of the device may 45 be varied to produce the novel features herein claimed and to advantageously combine the same with other elements employed in con-

nexion with buckles and loops on garment straps, or the like. As illustrated, however, the bar 8 is flattened throughout its substantial length and in a plane perpendicular to the plane of the buckle frame, as illustrated 55 and claimed in Letters Patent issued to the applicant on May 28, 1929, Number 1,714,924, and in addition thereto the flattened surface of the bar 8 is provided with spaced cupped formations 11 and 12 for registration with 60 the points of the prongs 6 and 7, respectively, as illustrated by the Figures 2 and 4, being thus adapted to cover and protect the points when moved into close contact therewith.

To thread the strap into the buckle the 65 strap may be thrust sidewise down between and under both prongs 6 and 7 so that the strap lies flatly upon the sliding bar 8, the free end of the strap being passed from the front of the loop buckle therethrough to hang 70 down behind the button loop portion of the device. Upon the tightening of the strap around the bar 8 exerts an upward sliding 75 tendency upon the sliding bar 8 to move and maintain the same in close contact with the prongs 6 and 7 which, having penetrated the strap, are covered by their respective cupped formations 11 and 12 provided by the bar 8 and which protect the prong points as illustrated by the Figure 3. To release the strap for adjustment from its holding engagement 80 within the buckle, the device is bodily tipped outwardly from the top, the tipping movement releasing the strap from the prongs and 85 forcing the sliding bar downwardly, thus giving the threaded strap a free running course through the buckle. The mere righting of the device and a taut strap will again engage the prongs with the strap and urge 90 the sliding bar into protecting engagement with the prong points.

The loop buckle is reversible in that the elevation as illustrated by the Figure 1 is substantially identical with the reversed elevation thereof (not illustrated).

I claim:

1. A loop buckle comprising a button loop supporting a frame provided with a fixed inwardly directed prong, and a bar mounted 100

upon the frame for a relative sliding movement into and out of engagement with the prong, the sliding bar carrying means for covering the prong end.

- 5 2. A loop buckle comprising a button loop supporting a buckle frame provided with fixed prongs inwardly directed toward the supporting loop, and a bar mounted upon the frame for a relative sliding movement into and out of engagement with the prongs, the sliding bar carrying means for covering the prong ends.
- 10 3. A loop buckle comprising a piece of wire of which the middle portion is bent to form a button loop, and the end portions are bent to form a substantially rectangular buckle frame, the wire extremities being bent inwardly within the frame and toward the loop to form spaced prongs, and a wire bar having 15 ends looped around parallel arms of the frame for a relative sliding movement toward and away from the prong points, the sliding bar being provided with means for 20 covering the prong points.
- 25 4. A loop buckle comprising a piece of wire of which the middle portion is bent to form a button loop, and the end portions are bent to form a substantially rectangular buckle frame, the wire extremities being bent inwardly within the frame and toward the loop 30 to form spaced prongs, and a wire bar having its ends looped around parallel arms of the frame for a relative sliding movement toward and away from the prong points, the 35 sliding bar being provided with means for protecting the prong points.

JESSUP SALISBURY.
